FEELER DEVICE FOR LOOMS.

1,278,802.

Specification of Letters Patent. Patented Sept. 10, 1918.

Application filed December 17, 1915, Serial No. 67,318. Renewed October 26, 1917. Serial No. 198,740.

To all whom it may concern:

Be it known that I, ALONZO E. RHOADES, a citizen of the United States, residing at Hopedale, county of Worcester, and State of Massachusetts, have invented an Improvement in Feeler Devices for Looms, of which the following description, in connection with the accompanying drawings, is a specification, like characters on the drawings representing like parts.

The invention to be hereinafter described relates to looms, and more particularly to looms of that type wherein the weft or filling is automatically replenished prior to complete exhaustion of the weft or filling in the active shuttle.

Looms of this type are generally known as "feeler" looms and are equipped with a feeler device which contacts with the filling in the shuttle as the lay beats up, and when the amount of filling has become sufficiently reduced, the feeler device acts through a train of mechanism to initiate filling replenishment.

In some types of feeler mechanism, the feeler member contacts with and is held from movement longitudinally of the shuttle so long as a working supply of filling is present but is displaced longitudinally of the shuttle when the filling supply is substantially exhausted or exhausted to a predetermined amount, and such longitudinal displacement is utilized to initiate filling replenishment.

Many disturbing factors are experienced in the practical use of such feeler mechanism, which tend to destroy their accuracy and reliability. Should these disturbing factors cause the filling to become fully exhausted before the feeler mechanism initiates replenishment, a defect in the cloth is liable to occur and thus defeat one of the purposes of the feeler mechanism; while, on the other hand, should the feeler mechanism act to effect replenishment while a working supply of filling yet remains on the bobbin or carrier in the shuttle, excessive waste is produced.

An important feature of the present invention, therefore, consists in a feeler mechanism wherein the feeler is displaced longitudinally of the shuttle by the contact pressure of the filling carrier or bobbin when the filling has become substantially ex-

hausted but is positively prevented from such movement during the presence of a normal or working supply of filling.

Another feature of the invention consists in means for freeing the feeler when the filling approaches substantial exhaustion, so that thereafter when such substantial exhaustion is reached, the feeler may be moved longitudinally of the shuttle by the contact pressure, or will be held from such movement by the feeler engaging the filling, should there still remain a working supply of filling in the shuttle after the feeler is released.

These and other features of the present invention will hereinafter be described in connection with one form or embodiment thereof as illustrated in the accompanying drawings, in which,

Figure 1 is a plan view of certain portions of a loom showing a good, practical form of the invention, the lay being indicated as in front position and the filling practically exhausted;

Fig. 2 is a section on the line 2—2, Fig. 1;

Fig. 3 is a plan view showing certain details and the relation of parts when there is a working supply of filling in the shuttle;

Fig. 4 is a section on the line 4—4, Fig. 3; and

Fig. 5 is a section on the line 5—5, Fig. 1.

The feeler member which is the part that enters the shuttle and feels for the filling, is represented at 1, and, like other feeler members, it is supported upon the loom frame in position to enter a slot 2 in the shuttle-box 3, as the lay 4 beats up, Fig. 1, and feel through a registering opening 5 in the side wall of a shuttle 6 to receive against its feeling end 7 the impact or pressure of the exterior of the wound mass of filling on the bobbin 8 or the impact of the bobbin itself as the case may be. The feeler member 1, also, like other feeler members, is mounted for movement toward the front of the loom under the impact of the filling in the shuttle and toward the rear by suitable yielding means. In the present instance, the feeler member 1 is mounted upon a carrier 10, which is formed as a slide, Fig. 3, adapted to reciprocate in a stand 11. The carrier or slide 10 is normally under the influence of a spring tending to move the feeler member to rearward position. In the

illustrated form of the invention in this respect, a spring 12 within the stand 11 surrounds the stem 13 of the slide and has one end seated against the wall 14 of the stand 5 and the other end bearing against the shoulder 15 of the stem 13.

The feeler member 1 is mounted upon the rear portion of the slide 10, so that on the beat-up movement of the lay the impact or 10 pressure of the filling in the shuttle against the feeling end of the feeler will cause the feeler and slide to move toward the front of the loom, and when the lay moves back, the said parts will return to initial position under the influence of the spring 12. To effect 15 lateral displacement of the feeler member lengthwise of the shuttle by the contact pressure when the supply of filling has become substantially exhausted, or exhausted to a 20 predetermined amount, the feeler member is pivotally mounted at 9 upon the slide 10 and is laterally offset, as indicated in Fig. 1, so that the forward impact or push of the 25 filling mass upon the feeler member may be exerted at one side of the pivot 9, thereby giving the feeler a tendency to swing about its pivot.

The feeling end 7 of the feeler member is roughened or serrated in a manner such 30 that should a working supply of filling be present in the shuttle as the lay moves forward on its detecting beat, the engagement of the filling with the roughened or serrated end of the feeler member will ordinarily prevent 35 movement of the feeler member in a direction longitudinally of the shuttle so that the feeler member under such conditions will ordinarily not swing about its pivotal mounting on the slide 10. Should the 40 filling have become substantially exhausted, however, when the end of the feeler member receives the impact, the roughened or 45 serrated end will strike either the exposed surface of the bobbin or between the few remaining coils of yarn, which will permit the end of the feeler member to move longitudinally of the shuttle under the forward pressure of the filling carrier as the lay beats up.

50 Operatively associated with the feeler member 1 is an actuator, which partakes of the forward and rearward movement of the member and when operatively positioned by longitudinal movement of the feeler member upon substantial exhaustion of the filling, said actuator is adapted to initiate filling replenishment through controlling means leading thereto.

In the present form of the invention, the 55 actuator is formed as a finger 16 extending forward from the pivotal point 9 of the feeler member and provided on its front edge portion with a notch 17 for engagement with a controller 18 under conditions 60 as will presently appear.

Rising from the stand 11 is an arm 19 having a recessed portion for the reception of a spring-pressed plunger 20, the end of which normally bears upon the side of the actuator 16 to maintain the actuator with 65 its end 17 in position, Fig. 3, so that upon frontward movement of the actuator it will normally fail to engage the end 21 of the controller 18. When, however, the filling has become substantially exhausted and the 70 feeler member 1 is caused to be moved longitudinally of the shuttle by forward push or impact of the filling carrier, as hereinbefore described, such feeler member will turn about its pivotal mounting and move the actuator 16 against the force of the spring-pressed plunger 20 to position the end 17 of 75 the actuator for engagement with the end 21 of the controller 18 as the feeler and actuator are moved frontward by further push 80 of the filling carrier on the feeler member as the lay completes its frontward movement.

The controller 18 is pivotally mounted at 85 22, Fig. 1, and its portion between such pivotal mounting and the end 21 of the controller passes through a slotted cam portion 90 23 of a transmitter 24 pivotally mounted at 25. This transmitter and the controller 18 may be of usual and well understood construction, and since they specifically form 95 no part of the present invention and are well understood by those skilled in the art, further description and illustration thereof will be unnecessary. It is sufficient to state 100 that upon frontward movement of the controller 18, under the conditions hereinbefore described, the transmitter 24 will be turned about its pivotal mounting 25 and through 105 conditions well understood and which form no part of the present invention, will initiate filling replenishment.

Owing to the delicacy of the feeler mechanism and the many disturbing influences that tend to destroy its accuracy and 110 reliability of action, it is desirable that the feeler member be positively prevented from movement longitudinally of the shuttle during normal weaving operations when a sufficient or working supply of filling is present 115 in the shuttle, and that it shall be relieved from such positive control when the supply of filling approaches substantial exhaustion, but before such substantial exhaustion is reached. The present invention, 120 therefore, contemplates means for positively locking the feeler member from movement longitudinally of the shuttle in response to the forward impact or push of the filling mass as the lay beats up, in addition to the roughened or serrated feeler end portion of 125 the feeler member, so long as a sufficient supply of filling is present in the shuttle to continue normal weaving operation, and to release the feeler member so that when the 130

filling has approached a certain degree of exhaustion, the feeler member itself will determine at what time after such release, filling replenishment should be initiated. In other words, after the feeler member has been unlocked by reason of approaching exhaustion, such feeler member will continue to be held from longitudinal movement of the shuttle so long as a working supply of filling is present therein, and when such supply has become substantially exhausted, such feeler member will be moved longitudinally of the shuttle by forward impact or push of the bobbin to initiate filling replenishment, as hereinbefore described.

As a convenient form of the invention in the respects noted, and to provide a good, practical form thereof for manufacturing purposes, the slide 10 has secured thereto at its rear portion, a stand 26, Figs. 2, 4 and 5, from which rises a lug 27, to the top portion of which the feeler member may be pivotally supported at 9 as hereinbefore described. The feeler member is carried downward as at 28, from its pivotal point above the lug 27, to present its feeler end portion in proper position for contact with the filling mass upon the shuttle.

The stand 26, which is preferably made separate from and secured to the slide 10, has bearing portions for a stud 29 on which is mounted a rocking feeler lock 30. The feeler lock 30 is extended forward from its pivotal support 29 and has a locking portion 31 which is adapted to engage the feeler member 1 forward of its pivotal mounting 9, the construction being such that when the locking portion 31 is in the path of movement of the feeler member portion front of the pivotal mounting 9, such feeler member cannot be moved longitudinally of the shuttle or turned upon its pivotal mounting by impact or pressure of the filling mass upon the end of the feeler member even though some disturbing causes may tend to produce this action. In order that the locking portion 31 of the feeler lock may be normally held in locking position, the stand 26 is provided with a seat in which is placed a spring 32 underlying the locking end 31 of the feeler lock, the construction being such that the locking end 31 of the feeler lock is normally held raised, or in locking position.

As hereinbefore noted, it is desirable that when the filling in the shuttle is approaching substantial exhaustion, the feeler member be freed from control of the feeler lock so that thereafter, should there still remain sufficient filling in the shuttle to permit continuance of working conditions, the feeler member will be prevented from movement longitudinally of the shuttle under the impact or pressure of the filling in the shuttle by the serrated or roughened end

thereof engaging the filling mass, but when the filling has reached substantial exhaustion, the feeler member may be moved longitudinally of the shuttle by the pressure of the bobbin against the end of the feeler member as the lay beats up, to thereby initiate filling replenishment.

To these ends, the feeler lock 30 is provided with an upwardly-projecting portion in which is adjustably mounted a threaded bolt or stud 33, which may be adjusted to contact with the front wall of the shuttle 6 when the filling in the shuttle has approached substantial exhaustion. By such contact, the feeler lock will be turned upon its pivotal mounting 29 and its locking portion 31 be removed from locking relation with the feeler member 1, so that the feeler member may thereafter, on each detecting beat of the lay, detect the condition of the filling in the shuttle, and be moved longitudinally of the shuttle only when the condition of the filling has reached substantial exhaustion.

It will be noted that the feeler member 1 contacts with the filling in the shuttle on each forward movement of the lay and thereby moves the slide 10 forward. This characteristic action of the feeler member continues throughout the operation, and longitudinal movement of the feeler member during the major portion of weaving the supply of filling from the shuttle is positively prevented and the feeler member locked; but when the filling supply approaches substantial exhaustion, but before such substantial exhaustion is reached, the feeler lock meets the side wall of the shuttle as hereinbefore noted, and causes the locking portion of the feeler lock to be withdrawn from locking position with relation to the feeler so that the feeler may thereafter act independently of the lock.

The stand 11 may be appropriately secured to the loom frame by any desired means, such, for instance, as the slot 34, Fig. 1, and bolts 35, and adjustment thereof in position to enter the openings in the shuttle wall and shuttle may be effected by suitable means such as the adjusting bolts 36.

In order that the locking portion 31 of the feeler lock may be prevented from rising too high under the influence of the spring 32, the feeler member may be provided with a side projection 37 beneath which the end 32 of the feeler lock may be confined.

It will be obvious that changes may be made in the relation of parts and their particulars of structure without departing from the true scope of the invention as defined by the claims.

What is claimed is:—

1. In a feeler motion for looms, the combination of a single feeler member having a portion to engage and be held by the filling

from movement longitudinally of the shuttle on each detecting beat until substantial exhaustion of filling and to be then moved longitudinally of the shuttle by the front-
5 ward push thereon, a lock for normally preventing filling control of the feeler until the filling has reached a predetermined degree of exhaustion and then freeing it that the feeler may be held from movements longitudinally of the shuttle by engagement with the filling alone until the filling becomes substantially exhausted.

2. A feeler motion for looms, comprising a single feeler to directly engage and receive the impact of the wound mass of filling in the shuttle on the forward movement of the lay to move the feeler forward, said feeler being constructed to be displaced longitudinally of the shuttle by the forward pressure 10 when the wound mass is substantially exhausted, a lock to prevent displacement of the feeler longitudinally while a working supply of filling is present in the shuttle and to free the feeler to such movement when 15 the filling approaches exhaustion, said feeler having an end portion to engage the remaining filling and prevent movement of the feeler longitudinally of the shuttle when freed from the lock control until the filling 20 reaches the desired degree of exhaustion.

3. A feeler motion for looms, comprising a feeler mounted for movement forward in unison with the lay by contact with the filling or carrier in the shuttle and for displacement longitudinally of the shuttle when the filling has reached such a degree of exhaustion that the feeler contacts with the surface of the filling carrier, a lock to prevent movement of the feeler longitudinally of the shuttle until the filling approaches exhaustion and to then free the feeler, said feeler having a single filling-engaging end portion for preventing movement of the feeler longitudinally of the shuttle after the feeler is unlocked provided a working supply of filling 45 is present.

4. A feeler motion for looms, comprising a feeler having a single contacting portion to receive the impact from the filling or carrier as the lay beats up to move the feeler forward, said feeler being mounted for displacement longitudinally of the shuttle by the forward pressure upon the feeler when the filling is substantially exhausted, 50 an actuator operatively combined with and to partake of the movement of the feeler, a controller adapted to be actuated by the forward movement of the actuator when the feeler has been displaced longitudinally of the shuttle, a lock normally acting to prevent feeler displacement longitudinally of the shuttle, and means actuated by movement of the lay for tripping the lock when the filling approaches substantial exhaustion, the single contacting portion of the

feeler acting, when the feeler is unlocked, to prevent longitudinal movement of the feeler until the filling has become substantially exhausted.

5. In a feeler motion for looms, the combination of a feeler slide, a stand secured to the feeler slide having a lug and a spring supporting seat formed integral therewith, a feeler on said lug having a single filling-engaging portion to engage the filling and be held thereby from movement longitudinally of the shuttle on each detecting beat until substantial exhaustion of filling and then be moved longitudinally of the shuttle by the forward push, a lock pivotally carried by the stand to prevent movement of the feeler longitudinally of the shuttle until the filling has reached a predetermined degree of exhaustion, a spring carried in the seat of the stand to maintain the lock in locking position and yield to permit unlocking movement of the lock that the feeler may be moved longitudinally of the shuttle when the filling by substantial exhaustion is no longer able to restrain such movement.

6. In a feeler motion for looms, the combination of a feeler slide, a stand secured to the rear portion of the feeler slide, a feeler, a feeler lock, and a spring seat carried by the stand, said feeler having a single feeler portion to be held from movement longitudinally of the shuttle by engagement with the filling after the feeler has been freed by the lock until substantial exhaustion of filling, and means actuated by the feeler for initiating replenishment of filling.

7. In a feeler motion for looms, the combination of a feeler carrier, a feeler member movable longitudinally of the shuttle by the forward push thereon and held from such longitudinal movement by engagement with the filling on a detecting beat until substantial exhaustion thereof, a lock for preventing movement of the feeler longitudinally of the shuttle until the filling has been depleted to a predetermined extent and then freeing the feeler to the control of the filling that the feeler may be held from movement longitudinally of the shuttle by engagement with the filling alone until substantial exhaustion of filling, and then be moved longitudinally of the shuttle by the forward push of the engaged surface within the shuttle.

8. A feeler motion for looms, comprising, in combination, a feeler member adapted to enter the shuttle and be moved longitudinally by the forward push on each detecting beat and held from movement longitudinally of the shuttle by engagement with the filling until substantial exhaustion thereof, a lock for preventing movement of the feeler member longitudinally of the shuttle and consequent disturbance of the filling.

by the feeler until the filling has reached a predetermined degree of exhaustion, and thereupon freeing the feeler member to the control of the filling, that it may be moved 5 longitudinally of the shuttle by the forward push of a surface within the shuttle, and means actuated by the feeler member

for initiating replenishment of filling when the feeler member fails to be held from movement longitudinally of the shuttle by 10 the filling on a detecting beat.

In testimony whereof, I have signed my name.

ALONZO E. RHOADES.
